CLAIM

The ornamental design for a video projector, as shown and described.

DESCRIPTION

FIG. 1 is a front left perspective view of a video projector, showing my new design;
FIG. 2 is a bottom right perspective view of a video projector;
FIG. 3 is a front view of a video projector;
FIG. 4 is a back view of a video projector;
FIG. 5 is a left view of a video projector;
FIG. 6 is a right view of a video projector;
FIG. 7 is a top view of a video projector;
FIG. 8 is a bottom view of a video projector; and,
FIG. 9 is a front right perspective view of a video projector. The broken line shown in FIG. 8 is included for the purpose of illustrating portions of the video projector and forms no part of the claimed design.
